UNITED STATES PATENT OFFICE.

JOHN B. MERKELS AND MATHIAS BIEVESHL, OF CHICAGO, ILLINOIS.

DESIGN FOR A COMBINED KEY-RING AND GUARD.

SPECIFICATION forming part of Design No. 23,242, dated May 1, 1894.

Application filed March 23, 1894. Serial No. 504,868. Term of patent 3½ years.

To all whom it may concern:

Be it known that we, JOHN B. MERKELS and MATHIAS BIEVESHL, citizens of the United States, residing at Chicago, in the county of Cook and State of Illinois, have invented and produced a new and original Design for a Combined Key-Ring and Guard, of which the following is a specification, reference being had to the accompanying drawing, which is made a part hereof, and in which the figure is an isometrical perspective view of a combined key-ring and guard of a new design.

A combined key-ring and guard of the new design has a ring-shaped portion A, and a hook-shaped portion B, united in the form of the letter S, and a stem C proceeding from said letter S. The end a of the ring-shaped portion is continued to within a very short distance of the central portion s of the S, so as to leave only a narrow space between them. The hook B embraces only about half a circle,

and its end b extends about parallel with the central portion s of the S, so as to leave a large opening between them. The stem C projects from the S in such direction that a line drawn through its longitudinal center and continued passes through the center of the hook B and is substantially parallel with the portions s and b. The stem has a bend at c, but this is a minor feature of the design, the essential features of which are the ring-shaped portion and the hook-shaped portion united in the form of the letter S, and the stem proceeding therefrom.

What we claim as new is—

The design for a combined key-ring and guard, substantially as shown and described.

JOHN B. MERKELS.
MATHIAS BIEVESHL.
